UNITED STATES PATENT OFFICE.

DAVID SCHULTZ, OF URBANA, INDIANA.

FOLDING EXTENSION-STEP.

1,164,226.

Specification of Letters Patent. Patented Dec. 14, 1915.

Application filed October 26, 1914. Serial No. 868,764.

To all whom it may concern:

Be it known that I, DAVID SCHULTZ, a citizen of the United States, residing at Urbana, in the county of Wabash and State 5 of Indiana, have invented certain new and useful Improvements in Folding Extension-Steps, of which the following is a specification.

This invention relates to railway rolling 10 stock, and more specifically to improvements in folding extension steps for passenger cars.

The object of my invention is to provide an additional step which, when in inoperative 15 position is retained beneath the fixed steps of a railway car, but which may be extended simply by the operation of a hand lever. When so extended it provides an additional step so close to the ground as to 20 do away with the necessity for placing a stool such as is customarily used to aid passengers in alighting from a car.

Furthermore, my device is extremely simple in construction and operation, durable, and so arranged that it may be added 25 as a part of the equipment of cars already in use, and does not require the installation of entire new car steps.

Other objects of this invention not at 30 this time more particularly enumerated, will be clearly understood from the detailed description and drawings forming a part of this specification.

Furthermore, this invention consists in 35 the novel arrangement and combination of parts more particularly described in the following specification and embodied in the claim appended hereunto and forming a part of this application.

Referring now to the drawings which are 40 merely illustrative of my invention; Figure 1 is a front elevation of my improved car step. Fig. 2 is a side elevation of the same. Fig. 3 is a vertical sectional view taken on 45 the line 3—3 of Fig. 1.

Referring further to the drawings, wherein 45 similar reference characters designate similar parts throughout the respective views, 1 designates the side pieces between 50 which are interposed in fixed position the conventional type of car step 2. An extension step 3 is centrally mounted upon U-

shaped hanger rods 4, said hanger rods being pivotally mounted at the ends of the upwardly extending arms thereof upon said 55 side pieces 1 at a point beneath the lowermost of said steps 2. A plurality of L-shaped members 5, have their longer arms secured upon the underside of the extension step 3 so that the shorter arms 6 thereof 60 will project slightly from the inner side of said step 3. A rod 7 is pivotally interposed between said side pieces 1 at a certain point in the rear of said steps 2. A lever 8 is fixed upon one end of said rod 7 and is 65 adapted to regulate the movement of said rod. A sector locking member 8^a is fixed upon one of the side pieces 1 adjacent the lever 8. Said sector locking member is provided with incut portions 8^b upon the outer 70 face near both ends thereof, said lever being adapted to seat within said incut portions respectively when the extension step is either in operative or inoperative position. A plurality of hinge members 9 are fixedly 75 mounted at one end thereof upon the rod 7, and pivotally mounted upon the short arms 6 of the L-shaped members 5 at the other end thereof, said hinges being provided with lugs 10 upon the hinged portions adjacent the pivotal point thereof 80 adapted to limit the forward movement of said hinges.

From the construction as described, it is obvious that by pulling the lever 8 upwardly 85 the extension step 3 will be moved forwardly into operative position, and that by moving said lever downwardly the extension step will be returned to a point beneath the steps 2. 90

The utility, adaptability, and advantages of my improved form of folding extension step being obvious, it is unnecessary to further enlarge upon the same herein.

Having now described and pointed out 95 the new and useful features of my invention, I do not limit myself to the shape of certain parts where the shape is not essential, nor do I restrict myself to the exact details of construction shown and described, but 100 mean and intend to claim all equivalents and variations thereof not departing in principle from my invention and falling within the purview of the appended claim.

What I claim as my invention and desire to secure by Letters Patent is:

In a railway car step, the combination of a plurality of U-shaped hanger rods pivotally mounted upon said step, an auxiliary step medially mounted upon said hanger rods, L-shaped rods secured upon said auxiliary step, a rod interposed between the sides of said car step, a lever mounted upon

one end of said rod, and a plurality of hinge members interposed between said rod and said L-shaped rods.

In testimony whereof, I affix my signature in presence of two witnesses.

DAVID SCHULTZ.

Witnesses:
